UNITED STATES PATENT OFFICE.

GEORGE H. BURLEY, OF TYRONE, PENNSYLVANIA.

DESIGN FOR A STEAM AND HOT-WATER HEATER-SECTION.

SPECIFICATION forming part of Design No. 29,506, dated October 18, 1898.

Application filed August 27, 1898. Serial No. 689,709. Term of patent 14 years.

To all whom it may concern:

Be it known that I, GEORGE H. BURLEY, a citizen of the United States, residing at Tyrone, in the county of Blair and State of Pennsylvania, have invented and produced a new and original Design for a Steam and Hot-Water Heater-Section, of which the following is a specification.

This invention relates to a new and original design for a steam and hot-water heater-section; and it has for its object to provide a design of this character that shall be both useful and ornamental.

The leading feature of the design resides in an approximately rectangular body provided at the top with a narrowed dome extension, a plurality of different-sized circular and oblong openings within its top portion, an angular arch at an intermediate point, an obtuse-angled cross-bar arranged below and parallel with said arch, and a series of vertical tubes arranged in the intervening space between said cross-bar and arch.

The foregoing constitutes the essential and distinctive features of the design claimed herein; but there are several minor features involved which may be enumerated as follows: a body provided with double beveled faces at the outer and inner sides of its leg portions, rounded corners on the dome extension thereof, sigmoidally-curved side-edge faces at the point where the dome extension is projected from the top of the body, and substantially U-shaped bosses projected from the inner sides of its leg portions at diametrically opposite points.

In the drawings, Figure 1 is a perspective view of the steam and hot-water heater-section embodying the herein-described design. Fig. 2 is an elevation thereof. Fig. 3 is a vertical sectional view on the line 3 3 of Fig. 2.

Referring to the accompanying drawings, the numeral 1 designates the body of the heater-section of an approximately rectangular shape and provided at the outer and inner sides of its vertical leg portions with longitudinally-disposed double beveled faces 1^a, the double beveled faces on the exterior side portions extending nearly the entire length thereof.

At its top the approximately rectangular section-body 1 has projected centrally therefrom a narrow dome extension 2, lying within

the plane of the body and of an inverted-U form in outline. The said dome extension 2 is provided with rounded corners 3, from which are projected offset notched webs 7, and between the oppositely-located webs 7 the dome extension 2 is further provided with a circular upstanding collar projection 8.

At the point where the body narrows into the dome extension 2 the side-edge faces thereof are sigmoidally curved, as indicated by the numeral 9, and at its lower side extremities the said body is further provided with offset horizontally-arranged rounded lobes 10, at one side of which are disposed outwardly-projecting collars 11.

Vertically-disposed notched webs 12 are projected from diametrically opposite side edges of the body immediately above the plane of the lobes 10 and collars 11, and within the top portion thereof, including the dome extension 2, the body is provided with a plurality of circular openings or figures 13 of different sizes and also with oppositely-located oblong openings or figures 14, and beneath the plane of these openings or figures the body is provided with a transverse angular arch 15. The diametrically opposite sides 16 of the body are connected by an interiorly-arranged obtuse-angled tubular cross-bar 16, which is disposed parallel with the angular arch 15 in a plane below the same, and a plurality of short vertical parallel tubes 17 are arranged in the space between the cross-bar 16 and the arch 15.

It will be observed that the under side of the angular arch 15, as well as the under side of the tubular cross-bar 16, is formed with double beveled faces, as plainly illustrated in Fig. 3 of the drawings, and to complete the design the said body is provided at diametrically opposite points on the inner sides of its leg portions with inwardly-projecting substantially U-shaped bosses 20.

What I claim is—

The design for the steam and hot-water heater-section herein shown and described.

In testimony that I claim the foregoing as my own I have hereto affixed my signature in the presence of two witnesses.

GEORGE H. BURLEY.

Witnesses:

D. M. WOLF,

GEORGE G. GIBSON.
